OIL BURNER

Boyd F. Castle, Quincy, Ill., assignor to
 The Quincy Stove Manufacturing Company,
 Quincy, Ill., a corporation of Illinois

Application July 16, 1943, Serial No. 494,963

7 Claims. (Cl. 158—91)

This invention relates to oil burners and has for an object to provide a durable and efficient device which will withstand prolonged operation on low or intermediate fire and which will burn with a clean hot fire under any demands made upon it.

Other objects will be set forth and apparent from a reading of the following specification.

In the accompanying drawings, I have illustrated one form of my invention. In such drawings,

Fig. 1 is a side elevation of the burner with the surrounding housing in section; and

Fig. 2 is a plan view with portions of the cap broken away;

Fig. 3 is a vertical section through the burner.

Like numerals refer to like elements throughout the drawings in which 10 designates the base generally. The base 10 comprises a bottom 10a and is provided with an upstanding flange 10b, shouldered near its top at 10c to provide a seat for a sleeve member 12. An aperture 10d is provided in the bottom of the base 10 for passage of air. A second flange 10e extends upwardly from the base member 10 and a small shoulder 10f is provided inwardly of and at the bottom of the flange 10e.

The base, as illustrated, is constructed to receive fuel oil and provides a chamber for oil and gases which is outwardly extended as indicated at 10x and convexed so that the flow of oil will be outwardly for gasification before it moves upwardly into the mixing and combustion chambers.

Oil or other fuel flows into the base 10 from a duct 11, in communication with a source of supply and under such control or regulation as is desired. An opening 10g is provided for ignition of the fuel.

Projecting upwardly from the flange 10b and seated on the shoulder 10c is the sleeve 12, provided with a plurality of apertures 12a. Surrounding and spaced from sleeve 12 is a shell 13, also apertured, as illustrated at 13a. The apertures 13a are substantially in alignment with apertures 12a and preferably larger. At the bottom, shell 13 is outwardly flanged at 13b to overlie the top of the base chamber.

The space between sleeve 12 and shell 13 is closed at the top by a cap 15 which is hollow and provided with outwardly directed aperture 15a in its periphery. Said cap is provided with shoulders or flanges 15b and 15c. Shell 13 is seated within flange 15b and sleeve 12 within flange 15c, serving to support the cap 15. The

bottom of the cap is apertured at 15d and flanged around said aperture at 15e to receive a depending tubular member 16, which extends downwardly to proximity with aperture 10d.

5 The sleeve and shell are encased within a surrounding and spaced member comprising a tubular sheet metal element 17, nested within the base flange, and resting upon the shoulder 10f. This element 17 extends part way up in parallelism to the sleeve and shell as illustrated in Fig. 3. Also a part of the encasing member is the sectional element 18, which is preferably formed of cast metal and corrugated, with the sections 18a slightly overlapping and loosely connected by stove-bolts 19 or the like. This element 18 surrounds the element 17 and its corrugations form air passages therewith as will be set forth more fully. It is preferable but not necessary to maintain element 18 out of substantial contact with the base so I provide the sections 18a with lugs 18c at the bottom and these rest upon the flange 10e of the base member.

10 The oil burner unit may be suitably mounted in an enclosing drum 20 having a bottom member 21 and provided with depending legs and feet 20a for support upon any suitable means permitting air to flow through the aperture 21a in member 21 and therefrom through base aperture 10d.

15 When starting my improved burner, fuel is introduced to the chamber in the base and ignited through the hole 10g. The fuel tends to flow toward the outer periphery of said chamber into 20 and around the extended portion 10x. As soon as sufficient heat is generated to vaporize or gasify the oil, such vapor or gas flows upwardly. Air moves into the sleeve which is closed at the top by the cap 15. Such movement, whether

25 caused by the natural draft or by fan or both, effects a flow of the air through apertures 12a of sleeve 12 into and through the chamber between the sleeve and the shell which is in the nature of a mixing chamber into which the gas or vapor 30 flows. Due to the arrangement of the apertures 12a and 13a, and the velocity of the air flowing through apertures 12a, an aspirating effect is caused, such air being jetted and continuing its travel through apertures 13a. In its passage

35 through the mixing chamber, the air commingles with the fuel gases and the aspiration of the jets of air and gas into the chamber between the sleeve 13 and the encasing members, which is in the nature of a combustion chamber, induces 40 further flow of gas or vapor from the base 10.

It should be noted that cap 15 also serves to close the mixing chamber at the top.

When normal operation is attained, the jets of air and gas will burn cleanly and efficiently in the combustion chamber. When the oil supply is regulated for "low fire," in the intervals of low heat demand, these jets will lie below the top of tubular member 17 and the heat of such jets, imparted to the tubular member, is conducted downwardly to the base member 19 and contributes materially to the gasification of the oil. At the same time, the corrugated case member 18 is protected from impact of the burning jets during low fire operation, which is constant, and from "intermediate fire," if so desired. The passages formed by the corrugations of member 18 and the tubular member 17 permit the flow of air upwardly between the two members on low fire. When a slight pressure is built up in the combustion chamber on high fire the products of combustion flow downward through the corrugations between these two members. This helps prevent high burning in the drum. It appears that jets will be burning from top to bottom of the shell 13 at high fire, while at low and intermediate fires, the jets at the upper and central portion or at the upper portion will not be contributing to the heating effect.

In short I am able, by control of my oil supply, to control the number and location of the burning jets, but the lowest or "low fire" jets are always burning and delivering heat. In principle, it is as if I were able to turn on or off at will the jets for high fire or for both high and intermediate fires by merely controlling the supply of oil.

The flange 13h, which I term a "gas ring," serves to obstruct or impede flow of gases directly from the base chamber into the combustion chamber and prevents burning at the bottom of the pot. At high fire or even at intermediate fire, any unburned gases arising from the combustion chamber, will encounter the jets of air issuing from the apertures 15a in cap 15 and will be scavenged, as it were.

The cast metal encasing sections 18a are capable of relative slip or movement when expanding or contracting and, by radiation, enhance the heating effect of the device as well as the efficiency of operation. Also formation of carbon is prevented on such members due to the intense heat imparted to them at other than low fire operation. Being virtually out of contact with the base member, as described above, substantial heat transfer from such members to the base is prevented.

The extension of the tube 16 downwardly nearly to the bottom of sleeve 12 demarcates the air for the cap apertures from the primary air supply to the sleeve and adds to the efficiency of operation.

While I have illustrated and described one embodiment of my invention, I do not wish to be considered as restricted to such embodiment except as limited by the appended claims, properly construed in the light of the prior art.

What I claim is:

1. An oil burner comprising an open topped base member having a fuel chamber and an aperture for passage of air, a sleeve mounted upon said base member in communication with said aperture, a co-axial shell spaced from said sleeve to form a mixing chamber therewith in communication with said fuel chamber, said sleeve and shell being provided with aligned apertures co-

acting to jet air from said base aperture into and through said mixing chamber, and encasing means surrounding and spaced from said shell to form a combustion chamber therewith for receipt and combustion of air and gases flowing from said mixing chamber, said encasing means including a sectional member, the sections of said member being loosely associated to permit relative movement thereof.

10 2. An oil burner comprising an open topped base member having a fuel chamber and an aperture for passage of air, a sleeve mounted upon said base member in communication with said aperture, a co-axial shell spaced from said sleeve to form a mixing chamber therewith in communication with said fuel chamber, said sleeve and shell being provided with aligned apertures co-acting to jet air from said base aperture into and through said mixing chamber, and encasing means surrounding and spaced from said shell to form a combustion chamber therewith for receipt and combustion of air and gases flowing from said mixing chamber, said encasing means including a sectional member supported by but largely out of contact with said base member.

20 3. An oil burner comprising an open-topped base member having a fuel chamber and an aperture for passage of air, a sleeve mounted upon said base member in communication with said aperture, a co-axial shell spaced from said sleeve to form a mixing chamber therewith in communication with said fuel chamber, said sleeve and shell being provided with aligned apertures co-acting to jet air from said base aperture into and through said mixing chamber, and encasing means surrounding and spaced from said shell to form a combustion chamber therewith for receipt and combustion of air and gases flowing from said mixing chamber, said encasing means including a tubular member partially nested in said base member in contact therewith and extending upwardly therefrom, and a second tubular member surrounding said first tubular member and projecting upwardly therefrom, said second tubular member being corrugated to form open-ended passages with said first tubular member.

30 4. An oil burner comprising an open-topped base member provided with an aperture for the passage of air, a flange extending upwardly from said base member around said aperture, a second flange extending upwardly from said base member surrounding and spaced from said first flange, said flanges substantially defining the opening in the top of said base member, a sleeve extending upwardly from said first flange, a shell surrounding and spaced from said sleeve to form a mixing chamber therewith, said sleeve and shell being provided with aligned apertures coacting to jet air from said base aperture into and through said mixing chamber, and encasing means extending upwardly from said second flange and spaced from said shell to form a combustion chamber therewith for receipt and combustion of gases from said mixing chamber.

40 5. An oil burner comprising an open-topped base member provided with an aperture for the passage of air, a flange extending upwardly from said base member around said aperture, a second flange extending upwardly from said base member surrounding and spaced from said first flange, said flanges substantially defining the opening in the top of said base member, a sleeve extending upwardly from said first flange, a shell surrounding and spaced from said sleeve to form a mixing

chamber therewith, said sleeve and shell being provided with aligned apertures coacting to jet air from said base aperture into and through said mixing chamber, and encasing means extending upwardly from said second flange and spaced from said shell to form a combustion chamber therewith for receipt and combustion of gases from said mixing chamber, said encasing means comprising a tubular member contacting said second flange and a sectional member surrounding said tubular member and supported by said second flange.

6. An oil burner comprising an open-topped base member provided with an aperture for the passage of air, a flange extending upwardly from said base member around said aperture, a second flange extending upwardly from said base member surrounding and spaced from said first flange, said flanges substantially defining the opening in the top of said base member, a sleeve extending upwardly from said first flange, a shell surrounding and spaced from said sleeve to form a mixing chamber therewith, said sleeve and shell being provided with aligned apertures coacting to jet air from said base aperture into and through said mixing chamber, and encasing means extending upwardly from said second flange and spaced from said shell to form a combustion chamber therewith for receipt and combustion of

5 gases from said mixing chamber, said encasing means comprising a tubular member contacting said second flange and a sectional member surrounding said tubular member and supported by said second flange, said sectional member being spaced in part from said supporting flange and corrugated to form open ended passages with said tubular member.

10 7. An oil burner comprising an open-topped base member having a fuel chamber and an aperture for passage of air, a sleeve mounted upon said base member in communication with said aperture, a co-axial shell spaced from said sleeve to form a mixing chamber therewith in communication with said fuel chamber, said sleeve and shell being provided with aligned apertures coacting to jet air from said base aperture into and through said mixing chamber, and encasing means surrounding and spaced from said shell to 15 form a combustion chamber therewith for receipt and combustion of air and gases flowing from said mixing chamber, the fuel chamber in said base member being extended beyond said encasing means, the bottom of said base member being outwardly and downwardly inclined whereby fuel will be urged to flow into said extended portion of said base chamber.
